COMBINED STOP WATCH AND CARRYING CASE
THEREFOR

Wilhelm S. Hanhart, Gluckstrasse 37, Schwenningen
(Neckar), Wurtenberg, Germany

Substituted for abandoned design application Ser. No.
67,933, Dec. 18, 1961. This application Jan. 2,
1968, Ser. No. 10,388

Term of patent 14 years

Int. Cl. D10—02

U.S. Cl. D42—8

FIG. 1 is a front elevational view of a combined stop watch and carrying case therefor, showing my new design;
FIG. 2 is a rear elevational view thereof; and
FIG. 3 is a right-side elevational view thereof.
I claim:
The ornamental design for a combined stop watch and carrying case therefor, as shown.
